(57) **CLAIM**

(22) Filed: **May 21, 2001**

The ornamental design for a currency bills evaluating and counting device, as described.

(30) **Foreign Application Priority Data**

DESCRIPTION

Nov. 21, 2000 (JP) 2000-033254

FIG. 1 is a front elevational view of a currency bills evaluating and counting device showing our new design;
FIG. 2 is a rear elevational view thereof;
FIG. 3 is a top plan view thereof;
FIG. 4 is a bottom plan view thereof;
FIG. 5 is a left side elevational view thereof; and,
FIG. 6 is a right side elevational view thereof.
